UNITED STATES PATENT OFFICE

ARCHIBALD G. SHAVER, OF CHICAGO, ILLINOIS, ASSIGNOR TO THE REGAN SAFETY DEVICES CO., INC., OF NEW YORK, N. Y., A CORPORATION OF NEW YORK

AUTOMATIC TRAIN CONTROL SYSTEM, INTERMITTENT TYPE WITH ROADSIDE ENERGY

Application filed January 7, 1922. Serial No. 527,568.

This invention relates to a train control system, and more particularly to a train control system of the intermittent induction type, and has special reference to the provision of an induction system arranged to be operated by a block signalling system in response to "safety", "caution" and "danger" traffic conditions to produce "clear", "caution" and "stop" effects on the train.

Among the principal objects of my invention are the provision of an induction train control system in which train control means is operated by a plurality of independent roadside mechanisms cooperating with vehicle mechanism to produce "stop" and "proceed" effects in the train control means, one roadside mechanism being active for producing a "tripping" or "clearing" action of the train control means, and the other mechanism being operative for determining the further state of operation of the train control means and for resetting the same under "safety" and "caution" track conditions; the further provision of an induction train control system of this nature in which a roadside source of energy is employed for selectively energizing the cooperating vehicle and roadside mechanism in response to traffic conditions; and the still further provision of an intermittent induction train control system of the type disclosed in my copending applications Serial No. 422,598 of Nov. 8, 1920; Serial No. 506,595 of Oct. 10, 1921; and Serial No. 515,242 of Nov. 15, 1921.

To the accomplishment of the foregoing and such other objects as may hereinafter appear, my invention consists in the elements and their relation one to the other, as hereinafter particularly described and sought to be defined in the claims reference being had to the accompanying drawings which show preferred embodiments of my invention, and in which:

Fig. 1 is a diagrammatic view of several blocks of railroad track showing the roadside mechanism associated therewith,

Fig. 2 is a diagrammatic view of the vehicle carried mechanism and the adjacent portion of the roadside mechanism, and

Fig. 3 is a diagrammatic view of a modified form of roadside apparatus.

Referring now more in detail to the drawings and more particularly to Fig. 2 thereof, there is provided as disclosed in my co-pending applications above referred to, a train control mechanism which comprises the electromagnet M' active for controlling the operation of a combined reservoir and brake valve (not shown), the detailed construction of which is set forth in my Patent No. 1,411,526 of April 4, 1922. The electromagnet M' is controlled by a two element relay F-B; when the currents in the said elements are in phase, as under "clear" track conditions, the contacts 27, 28 and 49 controlled by the relay are caused to assume the full line position shown in Fig. 2; and when the currents in the elements are out of phase, as for example 180° out of phase, this existing under "caution" track conditions, the said contacts are caused to assume the inclined dotted line position; and when either relay element is de-energized, this taking place under "danger" track conditions, the contacts are caused to drop and assume a neutral vertical dotted line position shown in Fig. 2.

With this operation of the relay F-B, under "clear" roadside conditions the electromagnet M' is energized to produce a train "proceed" effect in the valve controlled thereby, the said electromagnet being normally energized from a train carried alternating current source of energy G' by the following circuit: generator G', conductor 36, coil of electromagnet M', conductor 48, contact 49 closed in full line position, and conductors 44, 38 and 50.

Under "caution" roadside conditions the train controlling magnet M' is placed in circuit with a speed circuit controller S so as to produce a vehicle speed restrictive effect, the magnet M' being energized when the train is proceeding below and being deenergized when the train is proceeding above a predetermined or permissive speed, the said circuit including the generator G', conductor 36, electromagnet M', contact 49 in oblique dotted line position, conductor 46, contact 47 of speed circuit controller S, and conductors 45,

44, 38 and 50. With this arrangement it will be seen that when the train is moving above the permissive speed the contact 47 will be opened to deenergize the magnet M', and when the train is proceeding below or at the permissive speed, said contact 47 will be closed to energize the magnet M' for maintaining the air brake in an inoperative condition.

10 Under "danger" track conditions with the contact 49 in vertical neutral position, the circuit to the electromagnet M' is opened, the electromagnet deenergized, and the valve controlled thereby operated to set the brakes of the train and to disconnect the engineer's brake valve from the main reservoir as disclosed in my above mentioned Patent No. 1,411,526.

20 For normally maintaining the relay contact 49 in either of its full or dotted line positions to maintain the unlimited speed or restrictive speed effects on the train, I provide a stick circuit including one element of the relay F-B and controlled by another relay R'.

25 For normal or unlimited speed conditions the stick circuit comprises the generator G', conductor 35, contact 33 closed, resistance 31, conductor 24, contact 28 closed in full line position, conductors 22, 21, 20 and 19, condenser

30 K2, conductor 53, relay element B, conductors 39 and 25, contact 27 in full line position, conductor 29, resistance 30, contact 32 closed, and conductor 34. The element F of the relay F-B is energized through the circuit

35 including the generator G' and conductors 50 and 51. Under these normal conditions the currents in the relay elements F and B are in phase and the contacts 27, 28 and 49 are maintained by the relay elements in the full line position by these circuits. The resistances 30 and 31 are provided for protecting against momentary short-circuit of the circuit to the generator G' under certain conditions of operation.

40 45 When the currents in the relay elements F and B are displaced in phase by 180°, this being a condition produced by means to be described hereinafter, the contacts 27, 28 and 49 are moved to the oblique dotted line position and are retained in this position by the train stick circuit comprising the generator G', conductor 35, contact 33, resistance 31, conductor 24, contact 28 closed in dotted line position, conductors 18, 17, and 39, relay element B, conductor 53, condenser K2, conductors 19 and 26, contact 27 closed in dotted line position, conductor 29, resistance 30, contact 32 and conductor 34. With this circuit it will be noted that the currents in the elements F-B are out of phase and the stick circuit will therefore maintain the contacts in their dotted line positions.

50 55 Under "danger" track conditions the described stick circuit is broken by the opening of contacts 32 and 33 controlled by the relay

R' in a manner to be described hereinafter, and the contacts 27, 28 and 49 assume the vertical dotted line position, with the result that the electromagnet M' is deenergized for application of the brakes of the train.

70 For controlling the positioning of the contacts 27, 28 and 49 of the relay F-B so as to impress upon the train controlling means M' a desired effect, I provide cooperating

75 vehicle and roadside magnetic means or elements, and more specifically vehicle and roadside inductoriums, the roadside inductoriums being preferably under the control of a block signalling system and being influenced by the

so same to respond to "safe", "caution" and "danger" track conditions and to indicate such conditions, and the vehicle inductoriums being arranged for movement over the road-

80 side inductoriums to cooperate with the latter to receive and transmit indications of the

85 same to the train circuits and more specifically to the relay F-B to correspondingly influence and operate the latter.

90 To these ends I provide a plurality of train or vehicle energy receiving inductoriums 3a and 4a which are connected to control the

95 elements of a two-element vehicle relay R, the said relay comprising the elements A and B', the inductorium 3a being connected to the relay element B' by means of the conductors

100 51 and 3', and the inductorium 4a being connected to the relay element A by means of the conductors 4' and 6', condensers K'' and K' being provided in the circuits of both in-

105 dicatoriums to render the circuits resonant; and for cooperation with the vehicle in-

110 dicatoriums 3a and 4a, I provide sets of road- side transmitting inductoriums, a set for each

115 section or block of the track such as A, B, C and D shown in Fig. 1, the track rails X being divided into the sections or blocks by

120 means of the insulated joints Y in a manner well understood in the art. The sets of in-

125 dicatoriums each comprise a plurality of transmitting inductoriums 1 and 2 arranged for cooperation respectively with the vehicle in-

130 dicatoriums 3a and 4a in the movement of the vehicle, the said roadside transmitting inductoriums 1 and 2 being adapted to be

135 selectively connected to and selectively ener-

140 gized by a roadside source of energy such as the alternating current generator G, the said selective connection and energization being made responsive to track or roadside condi-

145 tions. The inductoriums 1 and 2 are located

150 in each block, usually at the entrance or in

155 advance of the block to be protected, the in-

160 dicatoriums in block A, for example, being

165 located so as to control the vehicle or train

170 before the latter reaches the block B.

175 For selectively operating or energizing the inductoriums 1 and 2 from the roadside source of energy G, there are provided road-

180 side circuits controlled by a distant relay D'

185 and a home relay H' for each block, the con-

130

struction being such that normal energization of the home and distant relays H' and D' responsive to "clear" track conditions will effect the energization of both inductoriums 1 and 2, and the energization of these inductoriums with currents of like phase, while deenergization of the distant relay D' responsive to "caution" track conditions will effect the energization of the inductoriums 1 and 2 with currents of different phases, while with the deenergization of a home relay H' responsive to "danger" track conditions either of the inductoriums such as the inductorium 1 will be disconnected from the source of energy G and deenergized.

Thus under "clear" track conditions the inductoriums 1 and 2 are connected to the generator G to be energized with currents of like phase, the inductorium 2 being connected to the generator by means of the circuit comprising the conductors 2' and 6, condenser K , conductor 5, winding of inductorium 2, and conductors 4 and 3, and the inductorium 1 being connected to the generator G by means of the circuit comprising conductors 2' and 8, contact 11 closed upon energization of the home relay H' , conductor 21, front contact 13 closed by energization of the distant relay D' , conductor 15, condenser L , conductor 17, winding of inductorium 1, conductor 16', front contact 12 controlled by the relay D' , conductor 20, closed contact 10, and conductor 3 to generator G . With this construction and arrangement of parts it will further be seen that the inductoriums 1 and 2 of a block such as A are controlled by the home and distant relays H' and D' of the next succeeding block such as B, and that under "safety" track conditions these circuits will be maintained as described by the energization of the home relay H' of block B from the track battery of said block and by energization of the distant relay D' of block B by a circuit controlled by the home relay H' of the second succeeding block C, the said circuit comprising a source of energy E , conductor 18, coil of relay D' , conductor 19, and contact 9 controlled by the home relay H' of block C.

When under "caution" track conditions a train is present in the second succeeding block C, causing the deenergization of the home relay H' of that block, the distant relay D' of block B is deenergized and the contacts 12 and 13 controlled thereby will be actuated to reverse circuit connections between the generator G and the inductorium 1, the contacts 12 and 13 being moved to engage the back contacts connected to the conductors 15 and 16' respectively, the reversal of circuit connections effecting the energization of inductorium 1 with current different in phase from the current in the inductorium 2.

Under "danger" track conditions, as when a train is present in the block B, the relay

H' of said block B is deenergized and the contacts 10 and 11 controlled thereby are opened for opening the circuit to the inductorium 1 and for effecting the deenergization of the latter.

With this construction it will be seen that in the movement of the train or vehicle and in the passage of the vehicle inductoriums over the track inductoriums, impulses will be selectively transmitted from the roadside transmitting inductoriums 1 and 2 to the vehicle receiving inductoriums 3a and 4a for selectively energizing the relay elements A and B' of the two-element relay R with currents of like or opposite phase and for deenergizing one of the said elements in response to traffic conditions, the cooperation between the train and track inductoriums being controlled by the circuit make and break and the pole changing device controlled by the home and distant relays of the block signalling system. It will be noted that the cooperation between the train and track inductoriums is momentary as the former moves over the latter in the movement of the vehicle.

Controlled by the relay R there are provided contact armatures 8 and 9 which under normal conditions assume the vertical dotted line positions shown in Fig. 2 due to the normal deenergization of the relay R, the said contacts being moved to the full line position shown when the elements of the relay R are energized with currents of like phase, and being moved to the oblique dotted line position shown when the elements of the said relay R are energized with currents of opposite phase.

When under "safe" track conditions the vehicle and roadside inductoriums cooperate for energy transference therebetween, and the contacts 8 and 9 are made to momentarily assume a full line position, the momentary closing of said contacts is effective for momentarily energizing the relay element B of the relay F-B with a current in phase with the current energizing the companion element F of said relay by means of the circuit comprising the generator G' , conductors 50 and 14, contact 9 in full line position, conductors 15, 20 and 19, condenser K_2 , conductor 53, relay element B, conductors 39, 16 and 13, contact 8 in full line position, and conductors 12 and 51, this momentary energization of the element B causing the contacts 27, 28 and 49 thereof to assume the full line position shown in Fig. 2 to close the stick circuit and the circuit of the electromagnet M, producing "clear" or "proceed" conditions on the train.

When under "caution" track conditions the train and track inductoriums cooperate for energizing the relay R to cause the contacts 8 and 9 thereof to momentarily assume the dotted line position, the momentary clos-

ing of the contacts effects the closing of a circuit to the relay element B for energizing the same with current out of phase with the current normally energizing the companion relay element F, the said circuit comprising the generator G, conductors 50 and 14, contact 9 closed in dotted line position, conductors 11, 16, 17 and 39, relay element B, conductor 53, condenser K2, conductors 19, 20, 15 and 10, contact 8 closed in dotted line position, and conductors 12 and 51. With the closing of this circuit the relay element B is energized as referred to by current of "an opposite phase", and the contacts 27, 28 and 49 are moved to the inclined dotted line position to close the stick circuit and the circuit including the electromagnet M' and the speed controller S, producing "caution" or speed restrictive conditions on the train.

When under "danger" track conditions the inductorium 1 is deenergized, the relay R remains unenergized and the relay element B is therefore not energized, and should the contacts 27, 28 and 49 be in the vertical dotted line position, said contacts will remain in such position for producing a "stop" effect upon the train.

For the purpose of conditioning the vehicle carried mechanism for operation and control by the train and track inductoriums so that the train circuits are made to respond to the indications of the track inductoriums, and for the purpose of tripping or "clearing" the train circuits in each section or block, there are provided cooperating train and track magnetic means for periodically deenergizing the relay F-B, and more specifically either stick circuit thereof at the contacts 32 and 33. To this end the relay R' heretofore mentioned is provided, said relay being connected to be normally energized from the train source of energy G' by means of the circuit including the said source of energy, conductor 52, coil of relay R', conductor 37, condenser K4, inductorium M and conductors 38 and 50, the condenser K4 being provided in this circuit for placing said circuit normally in a state of resonance. The inductorium M constitutes or comprises a trip device for the train circuits, the said inductorium cooperating with an inert track element S' provided for each section or block of the track, the cooperation between the inductorium M and a track element S' taking place when the former moves over the latter in the movement of the vehicle, the cooperation being such that when the inductorium M moves over an inert element S', the state of resonance of the circuit including the said inductorium is destroyed, such that the voltage at the terminals of the relay R' is considerably decreased. The adjustment of the contacts 32 and 33 of this relay R' is such that with the circuit in a state of resonance, the contacts are closed, but with the de-

creased voltage produced when the state of resonance of the circuit is destroyed, the contacts are opened for opening the stick circuit controlled thereby. With this construction it will therefore be seen that normally when the train is running between track elements S-S' the train circuits when running under "safe" or "caution" conditions will be so maintained by the closing of the stick circuit and when the inductorium M covers a track element S', the said stick circuit will be broken and the relay F-B will be deenergized, causing the contacts controlled thereby to move to neutral position for producing "stop" effects on the train. The inductorium M and the inert element S' present therefore a tripping mechanism for the train circuits, conditioning the same for response to the operation of the train and track inductoriums heretofore described, the train and track inductoriums being brought into cooperative relation substantially when or immediately after the tripping action takes place, the time interval between the tripping operation and the pick up operation of the inductoriums being insufficient to permit the brakes of the train to be set, the inductoriums functioning as a resetting or controlling mechanism for the train circuits responsive to traffic conditions.

The operation of the system thus far described will in the main be apparent from the above detailed description thereof. It will be seen that in each section or block the inert magnetic element S' of the track mechanism will momentarily destroy the resonance of the circuit of the inductorium M, causing a deenergization of the relay R' and an opening of the stick circuit to the relay element B for effecting the release of the contacts controlled thereby. Immediately after this action the train and track inductoriums are brought into cooperation to determine the further state of operation of the relay element B. Under "safe" track conditions impulses are transmitted to the train receiving inductoriums 3a and 4a to momentarily energize the relay R to actuate contacts 8 and 9 for the closing of a circuit to the relay element B to energize the same with an "in phase" current, such energization resulting in the contacts controlled thereby assuming their full line position for closing the stick circuit and the circuit to the electromagnet M, the said stick circuit being thereafter maintained closed by the re-energization of the relay element B due to the passage of the inductorium M beyond the track element S'. Under "caution" track conditions impulses will be transmitted to the train inductoriums 3a and 4a for momentarily energizing the relay R for effecting the momentary closing of an energizing circuit to the relay element B with an "out of phase" current for moving the contacts 27, 28 and 49 to their dotted line

position, placing the train under speed restrictive operation. Under "danger" track conditions no impulse is transmitted to the train inductorium M_2 with the result that the 5 relay element B of relay $F-B$ remains deenergized and the contacts controlled thereby remain in neutral circuit opening position for bringing the train to a halt.

After the train has been brought to a halt, 10 the same may be again set in motion by the operation of a release key Q , which is located or positioned in a normally inaccessible place on the vehicle operated by the engineer so as to cause the contact elements thereof to connect the generator G' to the relay element B of relay $F-B$ for energizing said element with "out of phase" current by means of the circuit including generator G' , conductors 50 and 40, upper contact of key Q , conductor 39, 15 relay element B , conductor 53, condenser K_2 , conductors 19, 20, 21 and 23, lower contact of key Q and conductors 41 and 51, this circuit causing the energization of the relay element B with an "out of phase" current so that the 20 armature contacts controlled thereby will be moved to the inclined dotted position, thus placing the speed circuit controller in circuit with the electromagnet M' so that the train can proceed under or at a predetermined 25 speed only.

Referring now to Fig. 3 of the drawings, I show a construction in which in lieu of tripping the train circuits in each block or in each section of the block as heretofore described, the said circuits may be tripped only when a "stop" condition is to be imposed upon the vehicle. The object of the arrangement shown in Fig. 3 is thus to obviate an imposing of the "stop" condition on the vehicle excepting when a condition requiring a train to stop exists. To accomplish this, a winding is placed upon the magnetic trip element M_2 such that when a control relay such as the track relay H_2 is energized, as under normal 45 conditions, the coil surrounding the track element M_2 is closed upon itself through the circuit including the said coil, conductor 41, armature 40 closed and controlled by the track relay H_2 , and conductor 42. When in 50 this condition the inductorium M comes into correspondence with or moves over the track element M_2 , the state of resonance existing in the circuit of the train relay R' is not sufficiently disturbed to operate the relay, but 55 when the track relay H_2 is deenergized so that the contact 42 is opened, then the operation of the element M_2 is the same as that of the element S' heretofore described, a tripping of the train circuits being then effected.

60 Thus with the inductive system of Fig. 3, the vehicle carried circuits or mechanism are deenergized or tripped only under predetermined roadside conditions such as a "stop" or "danger" condition. When the vehicle 65 carried mechanism is thus tripped or deener-

gized and the train brought to a halt, the same may be again set in motion by the operation of the release key Q as set forth above, this operation of the release key placing the train under a speed restriction, the train circuits being then operative as under "caution" conditions. With the train thus running under an imposed speed restrictive operation, no change in the vehicle circuits will take place when the train enters a "caution" block. When the train, however, running under these imposed speed restrictive conditions, enters a "clear" block, the vehicle carried mechanism or circuits will be restored to the "clear" position by the roadside inductors 1 and 2, this taking place even through the trip element M_2 is in closed circuit condition. Under such clearing conditions the vehicle relay R is energized to close the contacts 8 and 9 which is effective for substituting the clearing circuit for the relay BF for the then existing "caution" circuit thereof. It will be noted that the existing "caution" circuit includes the resistors 30 and 31 and therefore the current in the clearing circuit of this relay not only opposes but dominates the current in the "caution" running circuit of this relay. During a clearing operation the opposing currents will first deenergize the relay BF and the clearing current will then be effective for operating the relay BF to the "clear" position, the net result being the production of a clearing effect.

When the train running under "clear" conditions enters a "caution" block, the vehicle carried mechanism or circuits are operated to the "caution" position, this being accomplished by the energization of the relay R to move and close the contacts 8 and 9 to or in their right-hand dotted line positions, this being effective for substituting the "caution" circuit of the relay BF for and in lieu of the then existing "clear" circuit thereof. It will be again noted that the then existing "clear" circuit includes the resistors 30 and 31, and therefore the current in the substituting "caution" circuit of the relay BF not only opposes but dominates the current in the "clear" circuit of the relay. Here again during the change of operation the opposing currents will first deenergize the relay BF and the "caution" current will then be effective for operating the contacts of the relay BF to the "caution" position, the net result being the movement of the contacts of the relay BF to the "caution" position.

While I have shown my device in the preferred forms, it will be apparent that many changes and modifications may be made in the structure disclosed, without departing from the spirit of the invention, defined in the following claims.

I claim:

1. In an inductive train control system, in combination, a plurality of roadside induc-

5 toriums, a roadside source of energy connected to one of said inductoriums, means for connecting the source of energy to the other of said inductoriums comprising provisions for breaking circuit connections therebetween and provisions for reversing circuit connections therebetween, a home relay controlling the operation of said first mentioned provisions, and a distant relay controlling the operation of said second mentioned provisions.

10 2. In an inductive train control system, the combination with the track rails subdivided into a plurality of sections or blocks, of roadside mechanism comprising a plurality of inductoriums for each section or block, a roadside source of energy connected to one of said inductoriums of each block, means for connecting the source of energy to the other inductorium of each block comprising provisions for each block for breaking circuit connections between the source of energy and said inductorium, and provisions for each block for reversing said circuit connections, home and distant relays for each block, the home relay controlling the operation of said first mentioned provisions and the distant relay controlling the operation of said second mentioned provisions, the distant relay of one block being under the control of a home relay of the next block.

15 3. In combination, vehicle carried mechanisms, means including roadside mechanism for producing a controlling condition in the vehicle carried mechanism in the movement of the vehicle over a roadway, and means for influencing said vehicle carried mechanism for modifying said condition including a plurality of vehicle energy receiving inductor coils, a plurality of roadside energy transmitting inductor coils, and a roadside source of energy selectively connectable to for selectively energizing the said transmitting inductor coils.

20 4. In combination, vehicle carried mechanism, means including roadside mechanism for periodically influencing the vehicle carried mechanism in the movement of the vehicle over a roadway for producing a controlling condition therein, and means for influencing said vehicle carried mechanism for periodically modifying said condition including a plurality of vehicle energy receiving inductor coils, a plurality of roadside energy transmitting inductor coils, and a roadside source of energy selectively connectable to for selectively energizing the said transmitting inductor coils.

25 5. In combination, vehicle carried mechanism, means including roadside magnetic mechanism for influencing the vehicle carried mechanism in the movement of the vehicle over a roadway for producing a given condition, and means for influencing said vehicle carried mechanism for modifying said con-

dition including a plurality of vehicle energy receiving inductor coils, a plurality of roadside energy transmitting inductor coils, and a roadside source of energy selectively connectable to for selectively energizing the said transmitting inductor coils.

30 6. In combination, vehicle carried mechanism, means including roadside mechanism for influencing the vehicle carried mechanism in the movement of the vehicle over a roadway for producing a given condition, and means for influencing said vehicle carried mechanism for producing a different condition including a two element relay, a plurality of vehicle inductoriums one connected to each relay element, a plurality of cooperating roadside inductoriums, and a roadside source of energy selectively connectable to for selectively energizing the said roadside inductoriums.

35 7. In combination, vehicle carried mechanism including a normally closed operating circuit, means including roadside mechanism for opening the circuit in the movement of the vehicle, and means for determining the operation of said opened circuit including a plurality of vehicle energy receiving inductor coils, a plurality of roadside energy transmitting inductors, and a roadside source of energy selectively connectable to for selectively energizing the said transmitting inductors.

40 8. In combination, vehicle carried mechanism including a train controlling means and a speed controller, means including roadside mechanism for influencing the train controlling means in the movement of the vehicle for producing a given condition, means for influencing the train controlling means for producing another condition including a plurality of vehicle energy receiving inductor coils, a plurality of roadside energy transmitting inductors, a roadside source of energy selectively connectable to for selectively energizing said transmitting inductors, and provisions for placing the train controlling means under the control of the speed controller when the said transmitting inductors are energized in a predetermined manner.

45 9. In a train control system, a vehicle carried mechanism, means including roadside mechanism for influencing the same in the movement of the vehicle over a roadway, and means for determining the operation of the same when so influenced including a plurality of vehicle energy receiving inductor coils, a plurality of roadside energy transmitting inductor coils, and a roadside source of energy selectively connectable to for selectively energizing the said transmitting inductor coils.

50 10. In an inductive train control system, vehicle carried mechanism, means including roadside mechanism for influencing the same in the movement of the vehicle to produce a

- predetermined effect therein, means operable substantially when the same is so influenced for modifying the effect under given track conditions to produce a different effect therein, the latter means including a plurality of vehicle energy receiving inductor coils, a plurality of roadside energy transmitting means, and a roadside source of energy selectively connectable to for selectively energizing the said transmitting means.
11. In an inductive train control system, vehicle carried mechanism, means including roadside mechanism for influencing the same in the movement of the vehicle to produce a "danger" effect therein, means operable substantially when the same is so influenced for differently modifying the effect under "safe" and "caution" track conditions to produce "proceed" and speed restrictive effects therein, the latter means including a plurality of vehicle energy receiving inductor coils, a plurality of roadside energy transmitting means, and a roadside source of energy selectively connectable to for selectively energizing the said transmitting means.
12. In combination, train control means, means including roadside mechanism for influencing the train control means for producing a given condition, and means for influencing the train control means to produce a different condition therein comprising a two element relay for producing selectively different effects in said train control means, a plurality of vehicle inductoriums connected to the elements of said relay, a plurality of cooperating roadside inductoriums, a roadside source of energy, and means for selectively energizing said roadside inductoriums from said source of energy.
13. In combination, vehicle carried mechanism, means including roadside mechanism for influencing the vehicle carried mechanism in the movement of the vehicle over a roadway for producing a given condition, and means for influencing said vehicle carried mechanism for modifying said condition including a plurality of vehicle energy receiving means, a plurality of roadside energy transmitting means, a roadside source of energy, provisions for selectively connecting the source of energy to said energy transmitting means operative for changing circuit connections therebetween, and home and distant relays for controlling said provisions.
14. In combination, vehicle carried mechanism, cooperative vehicle and roadside means for producing a controlling condition in said mechanism under "stop" traffic conditions only, and means for influencing said mechanism under "proceed" traffic conditions to modify the controlling condition therein comprising a plurality of vehicle energy receiving means, a plurality of roadside energy transmitting means cooperating therewith, and a roadside source of energy for selectively energizing the said transmitting means.
15. In combination, vehicle carried mechanism, cooperative magnetic vehicle and roadside means for influencing said mechanism under "stop" traffic conditions only, and additional cooperative magnetic vehicle and roadside means for influencing said mechanism under "proceed" traffic conditions only, the said latter means comprising a plurality of vehicle energy receiving inductoriums, a plurality of roadside energy transmitting inductoriums cooperating therewith, and a roadside source of energy for energizing said inductoriums.
16. In a train control system, vehicle carried mechanism, means including roadside mechanism for producing a controlling condition in the vehicle carried mechanism under a predetermined traffic condition only, and means for modifying the controlling condition under a given traffic condition, the said latter means including a plurality of vehicle energy receiving means, a plurality of roadside energy transmitting means cooperating therewith, and a roadside source of energy for selectively energizing the said transmitting means.
17. In a train control system, vehicle carried mechanism, means including a roadside inductor for producing a controlling condition in the vehicle carried mechanism under a predetermined traffic condition only, and means for modifying the controlling condition under a given traffic condition, the said latter means including a plurality of vehicle energy receiving inductors, a plurality of roadside energy transmitting inductors cooperating therewith, and a roadside source of energy for energizing said inductors.
18. In combination, vehicle carried mechanism, means including roadside mechanism for influencing the vehicle carried mechanism in the movement of the vehicle over a roadway for producing a given condition therein, and means for influencing said vehicle carried mechanism for producing either of a plurality of other conditions including a plurality of vehicle energy receiving inductor coils, a plurality of roadside energy transmitting inductors, and a roadside source of energy selectively connectable to for selectively energizing the said transmitting inductors.
19. In combination, vehicle carried mechanism, means including roadside mechanism for producing a controlling condition in the vehicle carried mechanism in the movement of the vehicle over a roadway, and means for influencing said vehicle carried mechanism for modifying said condition to produce either of a plurality of other conditions therein including a plurality of vehicle energy receiving inductor coils, a plurality of roadside energy transmitting inductors and a roadside source of energy selectively connect-

able to for selectively energizing the said transmitting inductors.

20. In combination, vehicle carried mechanism, means including a roadside inductor for influencing the vehicle carried mechanism in the movement of the vehicle over a roadway for producing a given condition therein, and means for influencing said vehicle carried mechanism for producing either of a plurality of other conditions therein, the said latter means including a plurality of vehicle energy receiving inductor coils, a plurality of roadside energy transmitting inductors, and a roadside source of energy selectively connectable to for selectively energizing the said transmitting inductors.

21. In combination, vehicle carried mechanism, means including roadside magnetic mechanism for influencing the vehicle carried mechanism in the movement of the vehicle over a roadway for producing a given condition, and means for influencing said vehicle carried mechanism for modifying said condition to produce either of a plurality of other conditions therein, the latter means including a plurality of vehicle energy receiving inductor coils, a plurality of roadside energy transmitting inductor coils, and a roadside source of energy selectively connectable to for selectively energizing the said transmitting inductor coils.

22. In combination, vehicle carried mechanism, means including roadside mechanism for influencing the vehicle carried mechanism in the movement of the vehicle over a roadway for producing a given condition therein and means for influencing said vehicle carried mechanism substantially when the same is influenced by said roadside mechanism for producing either of a plurality of other conditions including a plurality of vehicle energy receiving inductor coils, a plurality of roadside energy transmitting inductor coils, and a roadside source of energy selectively connectable to for selectively energizing the said transmitting inductor coils.

23. In an inductive train control system, vehicle carried mechanism, means including roadside mechanism for influencing the same in the movement of the vehicle to produce a "danger" effect therein, means for differently influencing the vehicle carried mechanism for modifying the effect under "safe" and "caution" track conditions to produce "proceed" and speed restrictive effects in said vehicle carried mechanism, the latter means comprising a plurality of vehicle energy receiving inductor coils, a plurality of roadside energy transmitting inductor coils, and a roadside source of energy selectively connectable to for selectively energizing the said transmitting inductor coils.

24. In an inductive train control system, vehicle carried mechanism, means including roadside mechanism for influencing the same

in the movement of the vehicle to produce a "danger" effect therein, means for differently influencing the vehicle carried mechanism for modifying the effect under "safe" and "caution" track conditions to produce "proceed" and speed restrictive effects in said vehicle carried mechanism, the latter means comprising a plurality of vehicle carried energy receiving inductor coils, a plurality of roadside energy transmitting inductor coils, and a roadside source of energy selectively connectable to for selectively energizing the said transmitting inductor coils.

25. In combination, vehicle carried means operable to produce a predetermined condition of control, means adjacent to the track with which said means is cooperable to produce such condition, vehicle carried means for selectively modifying the controlling condition including a pair of receiving coils to receive impulses for operating such means, and a track device including a pair of impulse transmitting coils with which the receiving coils are cooperable substantially when the two first named means cooperate and means for selectively supplying the transmitting coils with electrical energy.

In testimony whereof I affix my signature
ARCHIBALD G. SHAVER.
